[57] CLAIM

The ornamental design for a combined lid and tray blank, as shown and described.

DESCRIPTION

FIG. 1 is a top plan view of a combined lid and tray blank showing my new design;

FIG. 2 is a top edge view thereof;

FIG. 3 is a right side edge view thereof;
The left side edge view being a mirror image thereof;

FIG. 4 is a bottom edge view thereof.

The solid lines represent — cutlines and the dashed lines represent — fold lines. The thickness of the blank is that of a conventional paperboard.
